Primary Examiner — T Chase Nelson

Assistant Examiner — Jonathan J. Han

(74) *Attorney, Agent, or Firm* — Quarles & Brady LLP

(57) **CLAIM**

The ornamental design for a shoe, as shown and described.

DESCRIPTION

FIG. 1 is a top, front, and right perspective view of an ornamental design for a shoe;

FIG. 2 is a right side view of the shoe of FIG. 1;

FIG. 3 is a left side view of the shoe of FIG. 1;

FIG. 4 is a front view of the shoe of FIG. 1;

FIG. 5 is a rear view of the shoe of FIG. 1;

FIG. 6 is a top view of the shoe of FIG. 1; and,

FIG. 7 is a bottom view of the shoe of FIG. 1.

The broken lines in the drawings illustrates portions of the shoe that form no part of the claimed design.

1 Claim, 6 Drawing Sheets
